(57) **CLAIM**

The ornamental design for a media player, substantially as shown and described.

DESCRIPTION

FIG. 1 is a front perspective view of a first embodiment of a media player in accordance with the present design;

FIG. 2 is a front view of the media player shown in FIG. 1;

FIG. 3 is a rear view of the media player shown in FIG. 1;

FIG. 4 is a left side view of the media player shown in FIG. 1;

FIG. 5 is a right side view of the media player shown in FIG. 1;

FIG. 6 is a top view of the media player shown in FIG. 1; and,

FIG. 7 is a bottom view of the media player shown in FIG. 1.

The phantom dashed lines (broken lines) showing the electrical and mechanical connectors are for illustrative purposes only and form no part of the claimed design.
